Patented June 12, 1917.

2 SHEETS—SHEET 1.

UNITED STATES PATENT OFFICE.

JONAS ALBERT JOHNSEN, OF CHRISTIANIA, NORWAY.

DEVICE FOR TRANSMITTING OR TRANSFORMING MICROMOVEMENTS.

1,229,619.

Specification of Letters Patent. Patented June 12, 1917.

Application filed December 31, 1915. Serial No. 69,541.

To all whom it may concern:

Be it known that I JONAS ALBERT JOHNSEN, a subject of the King of Norway, residing at Christiania, Norway, have invented 5 certain new and useful Improvements in Devices for Transmitting or Transforming Micromovements; and I do hereby declare the following to be a full, clear and exact description of the invention, such as will enable others skilled in the art to which it 10 appertains to make and use the same, reference being had to the accompanying drawings, and to letters or figures of reference marked thereon, which form a part of this specification.

In various apparatus it is required to transmit a rapid oscillatory movement from one member to another and in some cases at the same time to alter (increase or reduce) 20 the oscillations. This applies more particularly to devices such as microphones, telephones, gramophones, automatic recording devices, etc., and generally to any apparatus whose function is based or depends upon 25 what may be designated by the general term of micro-movements.

While the transmission of oscillatory movements by means of lever systems generally presents in mechanics no particular 30 difficulties, the simple law according to which the product of the lever by the power remains constant and which affords the necessary guidance for designing mechanisms of this nature for the transmission of micro- 35 movements by means of levers has presented difficulties which have not as yet been overcome. Many efforts have been made, for instance, to increase the strength of a microphone by connecting the diaphragm and 40 the member acting on the carbon box by means of a lever system or to transmit the oscillations of a primary swinging diaphragm to another one (the latter to perform increased movements) by means of a lever 45 system. These and several other endeavors have remained however without success the calculated or any increase at all of the oscillations or of the secondary effects of the 50 swinging member having failed to be realized.

I have now endeavored by numerous experiments to ascertain the origin of these difficulties and to provide means by which to obtain the desired results and in the following I shall briefly explain the results I 55 have arrived at.

The main reason why lever systems act otherwise with regard to micro-movements than with regard to common oscillatory movements and why micro-movements can 60 not be transmitted or transformed by means of levers according to the rules otherwise applying to lever systems lies in the weakness, the small amplitude and the sometimes complex character of the micro-movements 65 and also in the fact that such movements (more particularly sound waves) besides the direct effects of the elementary movement have also secondary effects due to the rapid succession of the movements. Thus, for example, a lever subjected to the action of sound waves will transmit the oscillations independent of the length of the lever arms in directions in which the oscillations shall be most easily able to put material in oscillatory 70 movements. In order to prevent a micro-movement imparted to a lever from being to any appreciable extent transmitted through the oscillating axis of the lever, and to provide that it shall be transmitted only 75 through its working arm, it is essential in the first place to concentrate a sufficient mass about the oscillating axis of the lever, to enable the inertia of said mass (analogously with an anvil) to prevent the lever from getting 80 into independent oscillations (which would be transmitted through its oscillating axis) or at any rate only to a minimum extent. I have found that with a lever consisting of one or more arms and of a body arranged in the above manner and by locating the fulcrum of the lever in or close to the center of gravity of the entire oscillating body, I am able to transmit the oscillations 85 through levers with the desired effect. 90

I have further found that it is essential for obtaining the desired result that the connection between the primary oscillating member and the lever be an entirely free contact, the lever being pressed, for example, 100 by means of a spring, against the said oscillating member. In order to obtain in practice an accurate equilibration of the lever it has proved advantageous not to support the pivots of the lever in bearings but to give 105 them a pointed shape and arrange them to be supported by holders resilient in an axial direction.

The present invention has for its object to utilize these results in devices of every 110 description in which an accurate transmission of micro-movements is required in con-

nction with an alteration, if any, (increase or reduction) of the movements or furtherance of certain oscillations in the case of combined or complex micro-movements.

5 Some examples of carrying out my invention will be described in the following specification reference being had to the accompanying drawings, in which:

10 Figures 1 and 2 show respectively in axial section and in plan the essential parts of a microphone with a lever system the object of which is to considerably increase the efficiency of the microphone.

15 Figs. 3 and 4 show a modified arrangement for the same purpose.

20 Fig. 5 shows diagrammatically a lever arrangement designed for use more particularly in cases where a very considerable increase of the oscillations is desired for example in the graphic record of sound waves.

25 Figs. 6 and 7 shows a modified arrangement of a microphone according to the present invention.

30 Figs. 8 and 9 illustrates a form of hook for connecting the diaphragm with the lever system.

35 Figs. 10-15 show details of three other forms of such hooks.

40 Figs. 16-21 show details of different forms of means for supporting the levers.

45 Figs. 22-25 illustrate a modification of a microphone according to the present invention, showing especially a preferable manner of mounting and connecting the microphone device proper with the casing.

50 Figs. 26-29 show two special forms of electrodes.

55 In Figs 1 and 2, 1 is a microphone diaphragm and 2 the carbon box which is located laterally in the microphone box and may be of any suitable construction. 3 is a lever connected at one end with a movable electrode 4 of the carbon box, which electrode may conveniently be of spherical shape so that it can be made thin and light. For the same reason the electrode may be made of aluminum which is carbonized on its active surface. The thickness of the lever increases from its tapering end toward the other end which is shown in the shape of a broad and thick boss 5 provided on its lateral faces with pins or pivots 6 which extend into corresponding recesses in the springs 7 which are secured to a projection 8 in the microphone box (it is of course sufficient for the purpose that one of the points be acted upon by a spring).

60 Instead of supporting the lever in the way just described I may make use of other arrangements for obtaining the result aimed at. As illustrated in Figs. 16 and 17, showing axial sections through the pivot ends of the lever boss I may obtain a laterally yielding bearing by placing a diaphragm or cap 31 on the end of the boss covering a de-

70 pressed portion 32 in the same. Said cap may, as shown in Fig. 16 be pressed on the boss outside the same or it may be inserted in the depressed portion as shown in Fig. 17. I may also support the lever by means of a spring thereby doing wholly away with a regular pivot arrangement. Examples of such supports are shown in Figs. 18 to 21.

75 In the form shown in Figs. 18 and 19 a flat spring 33 is fixed at its ends. The boss or pivot end of the lever is made in two parts 36 and 37 and secured to the spring in the manner shown so that the latter will act as a torsion spring when the lever vibrates.

80 In the form shown in Figs. 20 and 21 the boss is secured at its ends to spring 38 extending parallel with the lever from a fixed point of the microphone casing. The lever might also be supported by a single spring 85 attached in a similar manner to the boss in the center line of the lever.

85 The connection between the microphone diaphragm 1 and the lever 3 is as shown in Figs. 1-4 effected by means of a hook 9 90 screwed on to the diaphragm, the lever resting within the hook and being kept pressed against the same by a spring 10 secured to the lever. Figs. 8 and 9 illustrate a more suitable form of such a hook which permits 95 the diaphragm and the lever system to be easily disconnected.

90 The hook 11 is riveted to the diaphragm and has the form of a fork. The ends of the forks form each one half of a hollow pin 12. 13 is a screw which fits threads on the inside of the pin halves. The head 14 of the screw has a ridge or collar 15 which fits around the pin, so that when the lever has been inserted in the hook and the screw 105 is applied this collar will keep the pin halves together. The lever will then rest on the end of the screw and may be adjusted by means of the screw.

100 Other forms of hooks are shown in Figs. 110-15.

105 In Figs. 10 and 11 I have shown an arrangement in which the microphone diaphragm carries a short bifurcated screwstud 40; the hook 41 is provided with a flat shaft 115 42 fitting closely into the slot 43 of the screwstud and with a collar 44 serving as a bearing for a nut 45 by means of which the hook is secured to the screwstud. Adjustment of the distance between the edge of the 120 hook and the diaphragm may be obtained by means of a washer 46.

110 The form shown in Figs. 12 and 13 is a modification of the form shown in Figs. 10 and 11, a right and left-threaded nut 48 being used to connect the hook 47 with the screwstud 49.

115 The form of hook shown in Figs. 14 and 15 resembles the modification just described but in this instance the hook itself is split 130

so as to allow of easy insertion and removal of the lever in the eye of the hook without disconnecting the lever from the microphone box.

5 Although it is preferable to so arrange the axis of oscillation of the lever as not to have the latter carried by the diaphragm, satisfactory results may also be attained by placing the bearings of the lever directly on the diaphragm and such an arrangement is shown in Figs. 3 and 4. In this modification the lever arrangement is inverted, the lever itself abutting against a lug 16 secured to the diaphragm and being pressed against the same by a spring 10 secured to the lever and resting within the hook 17 secured to the diaphragm.

When it is desired to increase the micro-oscillations to a very large extent, it is preferable to use a bell-crank lever as shown diagrammatically in Fig. 5. In this figure 1 represents a diaphragm and 3 the pivot point of the lever. The long arm of the latter is composed of light rods 18, 19, the first one of which has a knee 21 against which a pointed lug 22 on the diaphragm abuts. 20 is the boss of the lever, and the lever is shown as being used for recording vibrations on a strip of paper.

20 Fig. 6 shows a microphone arrangement by which an increased efficiency is obtained by a system of two combined levers. The microphone box is in this case provided with bottom- and top-electrodes 24, 25 secured to one end of levers 26, 27, the lever 26 being single armed and the lever 27 double armed. A spring 28 secured to the lever 26 and abutting against the end of the lever 27 acts to keep either lever in contact with a hook 29 carried by the diaphragm.

45 The mode of operation of the arrangement, as will be seen, is such that an oscillation of the diaphragm in one direction will cause the operative ends of the levers to move away from each other, whereas an oscillation in the opposite direction will cause them to approach each other, and hereby the efficiency of the carbon box will be increased.

50 I shall now describe the microphone (embodiment my invention) shown in Figs. 22-25. Fig. 22 shows a section through the casing, the operative parts and the cover being removed. Fig. 23 is a section through the microphone box carrying the working parts of the microphone. Fig. 24 is a section through the cover. Fig. 25 is a plan view of the microphone box.

55 In the modification the working parts are marked with the same reference character as in Figs. 1-4. The diaphragm 1 is secured to the frame or box 50 carrying the other working parts by means of a ring 51 of angular cross section. This ring may be held by friction or by screw threads on the cir-

cumference of the box. The latter may be provided with screwthreads 52 corresponding with screwthreads 53 on the inside of the casing 54 or it may be held in the bottom of the casing simply by friction. The 70 cover 55 is after the insertion of the microphone box screwed on the same, whereby the contact springs 56 of the carbon box are pressed against the contact piece 57 on the inside of the cover. 58 is an electric connection between the boss of the lever and the microphone box or frame. This connection has proved useful for the reason that the electrical connection afforded by the bearing points of the lever is of such nature that it creates considerable resistance and therefore has disturbing effects on the microphone action. In this modification I have shown a carbon box of an oval form, which form has been found preferable for the following reason. When the electrode is carried by a lever as in the present invention the electrode will have a greater movement at its outer than at its inner end. This is to some degree a disadvantage and by making its radial dimension small and enlarging it sidewise this disadvantage is lessened. In this figure as well as in Fig. 1 it will be seen that the carbon box with the electrodes is so disposed that the inward movement of the diaphragm 90 causes the movable electrode to move out from the box, that is to say the pressure on the carbon grains is decreased, whereas in the usual arrangement this pressure is increased, when the diaphragm through the 100 sound waves is moved inwardly. This difference from the usual arrangement improves the sensibility of the microphone.

105 In Figs. 26 to 29 I have shown a special form of electrodes, which I have found preferable in connection with this invention.

In the form shown in Figs. 26 and 27 the electrode has a ribbed surface, the ribs being arranged in a direction so as to extend horizontally when the microphone is used, and 110 having in cross-section a sawtooth-like form with the sloping face turned upward. With this form the static pressure becomes less.

115 In the form of Figs. 28 and 29 corrugated electrodes are shown having the corrugations so disposed as to extend vertically when the microphone is used. In this form the corrugations in the two opposed electrodes have a peculiar form so as to secure the same distance between the two corrugated surfaces 120 throughout their extent. To this end the bottom of each corrugation has a round form as shown, the center of the arc being in the point of the opposed corrugation. In this manner I secure a greater efficiency of the 125 electrodes because the whole surface gets active and no dead corners are created as when the corrugations have a pointed shape at the bottom.

I do not limit myself to the manner of 130

- carrying out or using my invention as specified above. Lever mechanisms according to the present invention may be used to produce vibrations in electrical, optical or other apparatus by means of diaphragms or chords adapted to have oscillatory movements imparted thereto by sounding bodies. In this way desired synchronous effects may be realized by very simple means.
- Instead of connecting, as above stated, a single diaphragm or other primarily oscillating member with a plurality of operative organs, one may inversely connect a plurality of primarily oscillating organs with a single operative member (or with a plurality of such members).
- As regards the way of carrying out the invention it may be stated that a lever system may be composed of different materials so as to use, for example, a heavier material for the oscillating body with great mass concentrated around the oscillatory axis. It would also be possible to construct the entire oscillatory body as a body of revolution with a central portion of great mass and whose peripheral parts where the points of contact for the diaphragm or other oscillating members are located, may be in the form of a disk of light construction.
- When microphones according to the present invention are constructed for use on long lines, they may be provided with means whereby the action of the lever system may be lessened or neutralized. This may be done, for example, by means of pressure exerted on the diaphragm around its center, or by pressure on the lever or the oscillating body. It may also be done by an electrical resistance which is inserted in series or in parallel with the secondary conductor, or simply by employing a device similar to the socalled Iris-diaphragm used in photographic cameras.
- What I claim is:
1. In a device of the character specified, the combination with a primary oscillating member, of means for transmitting or transforming the oscillations of said member, a lever interposed between said member and said means comprising a lever arm having one of its ends attached to said means and an enlargement at the other end of said arm, said enlargement being a body of great mass relatively to the mass of the lever, means to pivotally support said enlargement substantially at the center of gravity of said enlargement and a connection between said lever and said primary oscillating member.
  2. In a device of the character specified, the combination with a primary oscillating member, of means for transmitting or transforming the oscillations of said member, a lever interposed between said member and said means comprising a lever arm having one of its ends attached to said means and
- an enlargement at the other end of said arm, said enlargement being a body of great mass relatively to the mass of the lever, means to pivotally support said enlargement substantially at the center of gravity of said enlargement and a connection between said lever and said primary oscillating member.
3. In a device of the character specified, the combination with a primary oscillating member, of means for transmitting or transforming the oscillations of said member, a lever interposed between said member and said means comprising a lever arm having one of its ends attached to said means and an enlargement at the other end of said arm, said enlargement being a body of great mass relatively to the mass of the lever, yieldingly supported bearings by which said enlargement is pivotally carried, and a connection between said lever and said primary oscillating member.
4. In a device of the character specified, the combination with a primary oscillating member, of electrodes for transmitting or transforming the oscillations of said member, a lever interposed between said member and said electrodes, said lever comprising a lever arm having one of its ends contacting with one of said electrodes and an enlargement at its opposite end said enlargement being a body of great mass relatively to the mass of the lever, yieldingly supported bearings in which said enlargement is pivotally carried, and a connection between said lever and said primary oscillating member.
5. In a device of the character specified, the combination with an oscillatory diaphragm, of means for transmitting or transforming the oscillations of said diaphragm, a lever interposed between said diaphragm and said means, said lever comprising a lever arm having one of its ends contacting with said means and an enlargement at its opposite end said enlargement being a body of great mass relatively to the mass of the lever, yieldingly supported bearings in which said enlargement is pivotally carried, and a spring actuated contact connection between said lever and said diaphragm.
6. In a device of the character specified, the combination with an oscillatory diaphragm, of means for transmitting or transforming the oscillations of said diaphragm, said means including a movable electrode, a lever interposed between said diaphragm and said means, said lever comprising a lever arm having one of its ends attached to said movable electrode and an enlargement at its opposite end said enlargement being a body of great mass relatively to the mass of the lever, yieldingly supported bearings in which said enlargement is pivotally carried, and a spring actuated contact connection between said lever and said diaphragm.
7. In a device of the character specified,

the combination with a primary oscillating member, of means for transmitting or transforming the oscillations of said member, a lever interposed between said member and 5 said means comprising a lever arm having one of its ends attached to said means and an enlargement at the other end of said arm said enlargement being a body of great mass relatively to the mass of the lever, yieldingly 10 supported bearings by which said enlargement is pivotally carried, and a spring actuated contact connection between said lever and said primary oscillating member, said connection comprising a hook secured to said 15 primary oscillating member in which hook said lever arm is supported.

8. In a device of the character specified, the combination with a primary oscillating member, of means for transmitting or transforming the oscillations of said member, a lever interposed between said member and 20 said means comprising a lever arm having one of its ends attached to said means and an enlargement at the other end of said arm 25 said enlargement being a body of great mass relatively to the mass of the lever, yieldingly supported bearings by which said enlargement is pivotally carried, a connection between said lever and said primary oscillating member, said connection comprising a hook secured to said primary oscillating member in which hook said lever arm is supported, and means for yieldingly pressing 30 said lever arm against said hook.

35 9. In a device of the character specified, the combination with a primary oscillating member, of means for transmitting or transforming the oscillations of said member, a lever interposed between said member and 40 said means comprising a lever arm having one of its ends attached to said means and an enlargement at the other end of said arm, yieldingly supported bearings by which said

enlargement is pivotally carried, and a connection between said lever and said primary 45 oscillating member, said connection comprising a hook portion secured to said primary oscillating member in which hook portion said lever arm is supported, and a screw and nut member adapted to engage said hook 50 portion.

10. A telephone transmitter or microphone, comprising a diaphragm, a lever having one of its ends enlarged and of great mass relatively to the body of the lever, a 55 pivotal support for the enlarged end of said lever, a connection between the diaphragm and the lever whereby the oscillations of the former are imparted to the latter, and means for transforming the oscillations of the lever into varied electric currents, said means comprising granulated carbon and oblong or oval electrodes in contact with said carbon.

11. In a device of the character specified, 65 the combination with a primary oscillating member, of means for transmitting or transforming the oscillations of said member, a lever interposed between said member and said means comprising a lever arm having 70 one of its ends attached to said means and an enlargement at the other end of said arm said enlargement being a body of great mass relatively to the mass of the lever, a connection between said lever and said primary oscillating member and yieldingly supported bearings by which said enlargement is pivotally carried, said bearings consisting of 75 pointed pins bearing against diaphragms.

In testimony that I claim the foregoing as 80 my invention, I have signed my name in presence of two subscribing witnesses.

JONAS ALBERT JOHNSEN.
